SPRAY NOZZLE TIP

Fred W. Wahlin, Oak Park, Ill., assignor to Spraying Systems Co., Bellwood, Ill., a corporation of Illinois

Application March 14, 1949, Serial No. 81,288

5 Claims. (Cl. 299—154)

1

My invention relates to spray nozzles and has reference more particularly to a construction of the outer end or tip portion thereof which improves the spray pattern and facilitates manufacture.

Spray nozzles of the character to which my invention relates are made with orifices of various sizes and shapes depending upon the capacity and pattern of spray required for the particular purpose for which the nozzle is intended to be used.

Generally, the pattern of the spray depends upon the shape of the orifice through which the spray is discharged, and these orifices, especially where the orifice is small, not only need to be made with a high degree of precision but also protected against any subsequent damage as any inaccuracy or alteration of the spray orifice greatly affects the pattern of the spray produced thereby.

To protect the orifice against damage it has been a common practice to recess the orifice in the discharge end or tip of the nozzle so that portions of the nozzle body project sufficiently beyond the outer end of the orifice to minimize exposure thereof to accidental injury. For this purpose many nozzles have a conical recess in the outer end with the nozzle orifice at the bottom of the recess.

For many purposes, nozzles are made with an elongated orifice, that is, with the exit narrow relatively to its length, to produce a wide flat spray and such nozzles have been made heretofore with a deep V-shaped notch extending across the nozzle end and at the bottom cutting through the rounded or dome shaped outer end of a passage, through which the fluid, usually liquid, is supplied from the interior of the nozzle to the spray orifice.

In such nozzles, however, the emerging liquid has a tendency to hug the opposite sides of the V-shaped notch sufficiently to affect the accuracy of the spray pattern.

This hugging effect is believed to be due, to some extent at least, to the aspirating effect of the emerging liquid which tends to impart movement to the surrounding air in the direction of movement of the spray with the result that air is drawn in through the V-shaped notch from each outer end thereof toward the emerging liquid.

As the direction of this entering air is directly against the edge portions of the emerging flat stream, it has a tendency to broaden the stream crosswise of the notch. Moreover, due to

2

the narrowness of the notch at the orifice, there is not sufficient clearance between the issuing stream and the sides of the notch at that location so that the air which enters from the two

5 ends of the notch can flow freely between the issuing stream and the side walls of the notch in the immediate vicinity of the orifice, and accordingly the aspiration effect of the stream necessarily produces a low pressure area at opposite sides of the issuing stream which, together with the direction of movement of the air in the groove, tends to cause or influence the issuing stream to hug the side walls of the V-notch as the stream leaves the orifice.

10 My invention is particularly applicable to nozzles of the above mentioned type which have the orifice at the bottom of a transverse notch or groove and seeks to improve the spray produced by such nozzles and insure greater conformity thereof to the orifice through which it is discharged.

15 Other objects of my invention are, to provide abrupt edges along the opposite sides of the orifice so that the spray stream leaves cleanly therefrom; to provide ample air flow to the opposite sides of the issuing stream and avoid any low pressure area there which might affect the accuracy of the stream; to increase the volume of air supply to the base of the issuing stream; 20 and to facilitate the manufacture of nozzles of grooved or notched end type—these and other objects being accomplished as more fully pointed out hereinafter and as shown in the accompanying drawing, in which:

25 Fig. 1 is a side view of a nozzle made in accordance with my invention;

Fig. 2 is an end view of the nozzle of Fig. 1 looking at the discharge end thereof;

Fig. 3 is a longitudinal sectional view of the nozzle taken on the line 3—3 of Fig. 1;

Fig. 4 is an enlarged fragmentary sectional view on the line 4—4 of Fig. 2 of the nozzle tip;

Fig. 5 is a view similar to Fig. 4 showing a modified form of orifice.

40 Referring to the drawing, the nozzle illustrated therein is composed of a body 10 having a large cylindrical opening 11 therethrough, a flat sided nozzle tip 12 which is made as a separate part and secured to the outer end of the body 10, a strainer 13 in the cylindrical opening 11 of the body and having an annular flange 14 at the outer end thereof interposed between the nozzle tip 12 and the outer end of the body 10, and a clamping member 15 by which the nozzle tip 12 is secured to the body 10.

45 50 55

The body 10 is internally threaded at 16 at its end remote from the tip 12 for connection to a pipe or other means through which liquid is supplied to the nozzle and the other end of the body is externally threaded at 17 for threaded connection therewith of the clamping member 15 which is of collar nut type with the outer end of the collar turned in as at 15a to engage over an annular flange 18 at the base of the nozzle tip for clamping the latter against the outer end of the strainer 13 and the strainer flange 14 against the outer end of the nozzle body. The clamping member 15 and body 10 each have a portion of the length thereof of external hexagonal form as indicated at 19 and 20 respectively, or of other suitable form for wrench engagement for conveniently securing the parts together.

The illustrated strainer 13 has a hollow cylindrical body 21 surrounded by a cylindrical screen 22 which is secured thereon by a screw 23 which is threaded into the lower end of the strainer body 21 and has a large head against which the lower end of the screen 22 abuts. The strainer body 21 has a series of transverse slots 24 through its wall, preferably at several places therearound, for example at diametrically opposed sides thereof, so that liquid introduced through the lower end of the nozzle passes through the screen into the interior of the strainer body 21, and the body 21 in the vicinity of said slots preferably is turned down to a size smaller than the interior of the screen 22 but with annular screen contacting ribs 25 left at suitable intervals, so as to allow free flow of liquid through a considerable area of the screen to the slots 24.

The nozzle tip 12 has a bored out cavity 26 communicating with the interior of the strainer body 21 and leading to a relatively small diameter bore or passage 27 with rounded or dome shaped outer end 28 through which the spray orifice 29 is formed.

This orifice 29 is recessed in the end of the nozzle at the bottom of a channel or groove 30 which extends across the nozzle end, the bottom of said channel or groove 30 being slightly beyond the dome shaped top 28 so as to leave only a thin wall of stock through which the orifice 29 extends.

An important feature of the present invention is that the channel or groove 30 is of rounded or other suitable form so that the bottom thereof, where the orifice 29 extends therethrough is relatively flat, thereby providing the orifice 28 with lateral margins 31 which are abrupt and with the channel or groove 30 widened out appreciably at the opposite sides of the orifice directly at the orifice 29 as shown particularly in Fig. 4.

This construction also facilitates the production of the orifice 29 as the groove 30 may be first cut across the end of the nozzle, with a rotary milling cutter, for example, of appropriate edge shape after which a V-edged rotary milling cutter may be plunged into the bottom of the groove 30 in parallel relation to the groove 30 and a sufficient distance to provide a small V-groove 32 of suitable depth at the center to cut through the dome shaped top 28 of the bore 27 and provide an orifice 29 of desired size and shape.

Because of the rounded or dome shape 28 of the outer end of the bore 27, the V-shaped cutter forms a long narrow orifice extending lengthwise of the groove 30 and it will be understood

that the size and shape of this orifice may be varied by changing the curvature or shape of the dome shaped end 28 of the bore 27 by changing the taper of the edge of the V-shaped cutter and 5 also by changing the diameter of that cutter.

Obviously the precision of the groove or channel 30 is not as important as the precision of the orifice 29 and because of the shallow cut 32 required in making the orifice 29 in the manner explained above there is little strain or wear on the V-shaped cutter and a very high degree of precision is maintained throughout a large number of operations.

Moreover, the shape of the orifice may also be 15 varied by constructing the orifice forming cutter of composite shapes. For example, by employing a flat sided cutter with V-edge and plunging the cutter a sufficient distance into the bottom of the groove or channel 30 an orifice may be formed as shown at 29a in Fig. 5 with the sides 20 29b of the orifice substantially parallel midway of the length of the orifice and tapered as at 29c at the opposite ends.

With a channel 30 formed as above, the angularity of the corners 31 at the opposite sides of the orifice are sufficiently close to 90 degrees so that the stream of liquid 33 (see Fig. 4) leaves the orifice 29 cleanly without any tendency to hug the side walls of the channel or groove 30, the latter being widened out at the lateral margins of the orifice 29 so perceptibly and to such extent that the air drawn in from each end of the groove or channel 30 by the aspirating effect of said stream 33 is free to flow along the channel or groove 30 into the spaces 34 at each side of the stream 33 and counteract any low pressure effect which might otherwise occur there and interfere with the accuracy of the stream discharge from the orifice.

Obviously the orifice 29 and channel 30 arrangement above described may be employed with any nozzle construction whether the tip portion 12 thereof is made as a separate part as herein described or as an integral part of the nozzle body and it is to be understood that my above described improvements in the tip portion of the nozzle are not limited to the particular type of nozzle shown and described herein but may be employed with any construction of nozzle to which they are applicable. Also other changes or modifications may be made without departing from the spirit of the invention, the scope of which is to be determined by the appended claims.

What is claimed is:

1. A spray nozzle having a relatively large groove extending directly across the discharge end of the nozzle from side to side thereof and opening at its opposite ends through said sides, 60 said groove being closed at its bottom by a wall which extends from end to end thereof and is formed in its top face with a relatively small groove of substantially less width than said large groove and extending lengthwise of said large groove midway between the sides thereof, said nozzle having a chamber therein which leads directly toward the bottom of the small groove and is closed at its end by said wall, said wall having an intermediate portion of said small groove extending therethrough and intersecting said closed end of the chamber crosswise and providing at the intersection a spray orifice which is encircled by a portion of said bottom wall and affords direct communication from the chamber 70 to and into the bottom of the small groove in a

direction upwardly toward the top of the small groove.

2. A spray nozzle having a relatively large groove extending directly across the discharge end of the nozzle from side to side thereof and opening at its opposite ends through said sides, said groove being closed at its bottom by a wall which extends from end to end thereof and is formed in its top face with a relatively small groove of substantially less width than said large groove and extending lengthwise of said large groove midway between the sides thereof, said nozzle having a chamber therein which leads directly toward the bottom of the small groove and is closed at its end by said wall, said wall having an intermediate portion of said small groove extending therethrough and intersecting said closed end of the chamber crosswise and providing at the intersection a spray orifice which is encircled by a portion of said bottom wall and affords direct communication from the chamber to and into the bottom of the small groove in a direction upwardly toward the top of the small groove, and provides the only communicability from the chamber to the small groove.

3. A spray nozzle having a relatively large groove extending directly across the discharge end of the nozzle from side to side thereof and opening at its opposite ends through said sides, said groove being closed at its bottom by a wall which is formed in its top face with a relatively small groove of substantially less width than said large groove and extending lengthwise of said large groove midway between the sides thereof, said nozzle having a chamber therein with a passageway of circular cross section leading outwardly therefrom directly toward the bottom of the small groove and terminating in a convexly rounded substantially hemispherical end with a portion of said bottom wall interposed between said end and said small groove, said wall portion having an opening therethrough which affords direct communication from the outer end of the passageway to and into the bottom of the small groove in a direction lengthwise of said passageway and directly toward the top of the small groove.

4. A spray nozzle having a relatively large groove extending directly across the discharge end of the nozzle from side to side thereof and opening at its opposite ends through said sides, said groove being closed at its bottom by a wall which is formed in its top face with a relatively small groove of substantially less width than said large groove and extending lengthwise of said large groove midway between the sides thereof, said nozzle having a chamber therein with a passageway leading outward therefrom directly toward the bottom of the small groove and terminating in a convexly rounded substantially hemispherical end with a portion of said bottom

wall interposed between said end and said small groove, said small groove being disposed to extend in the direction of its length across the convexly rounded end of said passageway in a position to intersect said end, and said bottom wall portion having at the place of intersection of the groove and passageway end an opening therethrough through which the groove and passageway intercommunicate directly into one another.

5. A spray nozzle having a body with a chamber therein and a removable tip detachably secured to the body and closing the chamber at one end, said tip being a single member having a portion thereof projecting outwardly from the nozzle body and provided with a relatively large groove extending directly across the outer end of the outwardly projecting portion from one side thereof to the other side thereof and opening at its opposite ends through said sides, said groove being closed at the bottom by a wall which is formed in its top face with a relatively small groove of substantially less width than the large groove and extending lengthwise of said large groove midway between the sides thereof, said member having a circular passageway therein which opens at one end into said chamber and extends outwardly from said chamber toward the bottom of said small groove and terminates in a convexly rounded substantially hemispherical end with a portion of said large groove bottom wall interposed between said convexly rounded end and said small groove, said small groove being disposed to extend in the direction of the length across the convexly rounded end of said passageway in a position to intersect said end, and said bottom wall portion having at the place of such intersecting of the groove and passageway an opening therethrough through which the groove and passageway intercommunicate directly with one another, said passageway and said opening conjointly providing the only communicability from the chamber to the small groove.
